CLAIM

The ornamental design for an exhaust pipe set for a minivan, substantially as shown and described.

DESCRIPTION

FIG. 1 is a partial perspective view of the present design showing an exhaust pipe set for a minivan; FIG. 2 is a rear view thereof;

FIG. 3 is a side view thereof, the opposite side being a mirror image thereof; and,

FIG. 4 is a top view of embodiments corresponding to the present design.

The bottom view is disclaimed herein. The portions of the design shown in broken/dashed lines are for illustrative purposes only and form no part of the claimed design. The illustrated article is not limited to the scale shown.
